UNITED STATES PATENT OFFICE.

FRANK WRIGHT, OF LONDON, ENGLAND.

COIN-FREED GAS-METER APPARATUS.

SPECIFICATION forming part of Letters Patent No. 548,494, dated October 22, 1895.

Application filed April 5, 1895. Serial No. 544,612. (No model.)

To all whom it may concern:

Be it known that I, FRANK WRIGHT, a citizen of England, residing at No. 21 Old Queen Street, Westminster, London, England, have 5 invented a certain new and useful Coin-Freed Gas-Meter Apparatus, of which the following is a specification.

My invention relates to coin-freed apparatus applicable to gas-meters so arranged that it can readily be applied to existing meters and can be worked by coins of two different values, such as pence and half-pence.

I shall describe apparatus according to my invention, referring to the accompanying 5 drawings.

Figure 1 is a perspective external view of an ordinary dry meter modified according to my invention. Fig. 2 is a plan with cover removed to show the internal mechanism. Fig. 3 is a section, partly in elevation, on the line X X of Fig. 2. Fig. 4 is a section, partly in elevation, on the line Y Y of Fig. 2. Figs. 5 and 6 are sections, respectively, on Z Z and W W of Fig. 2. Fig. 7 is a modified form of 5 wheel K.

V is the valve-shaft, which is caused to revolve in the usual way by the oscillating arms v v and links v' v', and which by worm-gear v² causes the spindle A of the counter to 10 revolve. On the spindle A is fitted, free to revolve a sleeve B, carrying a worm b, gearing with a wheel K of the coin-freed mechanism hereinafter described.

C is a disk fixed on the spindle A and having an arm D fitted to slide radially on it and urged outward by a spring d. The outer end of the arm D is thickened and has one side shaped as a tooth d'.

E is a disk loose on the sleeve B, but fixed 15 on the framing of the meter.

F is another disk, which by means of a rod f, projecting through a semicircular slot in the face of the counter, can be partly turned around the spindle A and can be held in any 20 desired position. Both the disks E and F have at their peripheries inwardly-projecting flanges cut away for half the circumference.

H is a toothed wheel fixed on the sleeve B.

As the counter-spindle A revolves it carries 25 around the disk C and arm D, the tooth d' of which, being held engaged with the teeth of the wheel H by the flange of the disk E or F,

causes the sleeve B to revolve, driving the coin-freed mechanism, but when after revolving a certain distance the end of D escapes 55 from under the flange of E or F its tooth d' becomes disengaged from H, and A goes on revolving without driving B until the end of D again passes under the flange of E or F, which causes its tooth d' to engage again with 60 and drive the wheel H. Thus every revolution of the spindle A causes a less or greater fraction of a revolution of the sleeve B, according as the disk F is set with a greater or less interval between its flange and the flange 65 of E, and consequently the wheel driven by B requires a greater or less number of revolutions of A, and therefore the passage of a greater or less quantity of gas to receive the 70 movement necessary to give effect to the action of the introduced coin.

The wheel K has its movements adjusted in the manner described, so that one-quarter of a revolution shall correspond with the delivery of so much gas as is of the value of the introduced coin, which may, for example, be a penny. If no provision is required for variation in the value of gas, the wheel K may be worked direct from the spindle A without intervention of any adjusting mechanism. In 80 either case the wheel K has through it at equal intervals four holes of the size to allow passage of a penny. Above the wheel K is fixed a cylinder L, having in its side a horizontal slot l for admitting the coin or a number 85 of the coins, and a heavy plunger l', which has to be raised by hand when a coin is to be introduced at l, and which, when let go, presses down the coin or coins below it. The cylinder L may also have a vertical slot, as shown 90 in Fig. 1, with an index l² attached to the plunger l' and showing on a scale how many coins there are under the plunger. On each side of the cylinder L, near its bottom, there is pivoted an arm l³, having a stepped lower 95 face which acts as a gravity-pawl, allowing one coin or several to pass under it and holding it or them down when passed.

M is the gas-supply pipe, which, instead of going direct to the slide-valves, as usual, is 100 interrupted at M' and has to pass through a valve-box containing a valve m, having its stem m' projecting up through a stuffing-box and pressed by a lever carrying an adjustable

load m^2 , so as to keep the valve m closed. When, however, a coin is introduced at b , or several of these, and the plunger l' is let down, as shown in Fig. 3, the stem m' is forced down, opening the valve m and allowing gas to flow by M^2 to supply the meter. The valve-spindle V , now revolving, drives the counter-spindle A and thus drives the sleeve B , which, through the worm-gear b , causes the wheel K to revolve. The coin, or the lowest of several coins in the cylinder L , is thus carried around with the wheel K until, after a quarter of a revolution, it comes over a hole N , through which it falls and passing down a chute lodges 15 in a receptacle R . If no other coin remains in L , the stem m' rises, closing the valve m ; but if there be several coins in L the meter will go on until the last of the coins has passed from above the head of the stem m' .

20 As the price of gas varies, the quantity delivered for the coin unit, such as a penny, can readily be varied by the adjustment of the flanged disks E and F . As an example of such adjustment I will assume that every revolution of A registers a passage of two cubic feet, that the wheel H has one hundred and twenty teeth, and that the sleeve B has to make ten revolutions for the passing of a penny through the coin-free mechanism, which requires a 25 quarter-revolution of the wheel K .

If the disk F be set so that the end of its flange coincides with the end of the flange of E , then the tooth d' is held engaged with the wheel H during the whole revolution of A , and consequently the penny introduced in the slot of the coin-free mechanism will purchase twenty cubic feet, the product of ten revolutions of A by the two cubic feet delivered at each revolution. If now the disk 30 F be turned around relatively to E so that there is between the ends of their flanges a gap uncovering sixty of the teeth of H , then as the tooth d' is driving half a revolution of A , disengaged from H , it will require twenty 35 revolutions of A to cause ten revolutions of B , and consequently the penny will purchase forty cubic feet. By turning F to intermediate positions various quantities between the minimum of twenty and the maximum of forty 40 cubic feet can be made to be delivered for a penny.

In what precedes I have described the coin-free mechanism adapted for only one coin, such as a penny. It may be readily modified,

as in Fig. 7, so as to adapt it for two coins, such as a penny and a half-penny, by making two of the holes through the wheel K opposite each other too small for passage of a penny, but large enough to pass a half-penny, and by adjusting the gear so that the gas purchased for a penny should correspond to half a revolution of the wheel K . As a half-penny is carried around by a hole of either size it is always dropped at one-quarter of a revolution; but assuming a penny to have been so dropped from a hole of its own size, then as the next hole cannot receive a penny the wheel has to make a quarter of a revolution before the next penny begins to move, and move another quarter revolution before dropping it, thus making altogether one-half revolution for the penny.

Obviously the size of the wheel K and the number of holes through it, also the proportions of the gearing connecting it to the counter mechanism of the meter, may be varied to suit the values of different coins and the price of the gas to be purchased.

I claim—

1. In coin freed gas meter apparatus the combination of a horizontal wheel adjustably geared to the counter gear of the meter and having through it holes for passage of coins a cylinder mounted above the wheel with a side slot for introduction of a coin and a heavy plunger, a gas valve arranged below the cylinder and kept closed by a loaded lever, also under another part of the wheel a hole for passage of coins to a chute and receptacle, substantially as and for the purposes set forth. 80

2. In coin freed gas meter apparatus, in combination with the counter spindle of the meter, a sleeve thereon, geared to the coin freed mechanism, and having on it a toothed wheel, a disk on the spindle carrying a spring slide 85 with a tooth adapted to engage with the wheel, two disks each inwardly flanged over half of its circumference and adjustable in position relatively to one another, substantially as and for the purpose set forth. 90

In testimony whereof I have signed my name to this specification, in the presence of two subscribing witnesses, this 12th day of March, A. D. 1895.

FRANK WRIGHT.
